UNITED STATES PATENT OFFICE.

SAMUEL D. RONALD, OF SAN FRANCISCO, CALIFORNIA, ASSIGNOR TO BETHLEHEM SHIPBUILDING CORPORATION, LTD., OF BETHLEHEM, PENNSYLVANIA, A CORPORATION OF DELAWARE.

ANGLE-BENDING MACHINE.

1,875,934.

Specification of Letters Patent. Patented Apr. 26, 1921.

Application filed December 4, 1918. Serial No. 265,199.

To all whom it may concern:

Be it known that I, SAMUEL D. RONALD, a citizen of the United States, residing at San Francisco, county of San Francisco, State of California, have invented a new and useful Angle-Bending Machine, of which the following is a specification.

In forming and rolling machines as heretofore constructed considerable difficulty has arisen owing to the overheating of the bending roll since it is customary to heat the angle or other bars of metal before they are bent and in some cases valuable time is lost in waiting for the bending rolls to cool off.

In accordance with my present invention, I employ a plurality of rolls which are carried by a rotatable tool carrying head which is capable of vertical adjustment and which is supported on a carriage which is capable

20 of lateral adjustment.

With the above in view my invention consists of a novel construction and arrangement of a bending machine which is especially adapted for the bending of angle bars, although as is apparent it is not limited to such use but may be employed for the bending into a desired form of any desired contour of metal or other bars.

My invention further consists of a novel construction of a bending roll and a novel construction of a die with which said bending roll co-operates.

It further consists of novel means for effecting the proper adjustment of a bending roll.

Other novel features of construction and advantage will hereinafter more clearly appear in the detailed description of my invention.

For the purpose of illustrating my invention, I have shown in the accompanying drawings a typical embodiment of it which in practice will give satisfactory and reliable results. It is, however, to be understood that this embodiment is typical only and that the various instrumentalities of which my invention consists can be variously arranged and organized and that my invention is not limited to the precise arrangement and organization of these instrumentalities as herein set forth.

Figure 1 represents, in front elevation, an angle bending machine embodying my invention.

Fig. 2 represents a side elevation of the machine.

Fig. 3 represents a section on line 3—3 of Fig. 1.

Fig. 4 represents a section on line 4—4 of Fig. 5.

Fig. 5 represents a section on line 5—5 of Fig. 4.

Similar numerals of reference indicate corresponding parts.

Referring to the drawings,

1 designates the base of a vertical boring mill of any desired or conventional type which is provided in the usual manner with a rotary table 2 having any desired means for effecting and controlling its rotation such as are well known in the art. In the form illustrated the construction just described is of the Bullard boring mill type. In this type of mill the table rotates and the working tool is stationary. The base 1 has rising from it a standard 3 having a laterally extending portion to which are connected end bars 4. The end bars 4 are connected by cross bars 5 and 6 on which a carriage 7 is slidable. 8 designates a nut on the carriage, see Fig. 4, adapted to receive a feed screw 9 which is journaled in the end bars 4. The feed screw 9 is manually adjusted to laterally position the carriage 7, the free end of said screw having a polygonal contour to adapt it to receive a working tool. The front face of the carriage is provided with guide-plates 10 which form vertical slots 11 in order to receive therein an adjustable slide 12. The slide 12 has, at its rear, a rack 13 which engages with a pinion 14 which has a key 15 which extends into the longitudinally extending keyway 16 of a shaft 17 on which said pinion 14 is loosely mounted, so that it will not interfere with the lateral adjustment of the carriage 7. The shaft 17 is journaled in the end bars 4 and has its free end of a polygonal contour to adapt it to receive a tool to rotate the shaft 17 and thereby effect the vertical adjustment of the head 12. The pinion 17 is mounted between straps 18 secured to the carriage 7.

19 designates a stud shaft at the lower end of the head 12, and rotatably adjustable on the stud-shaft 19 is a tool carrying head 20 which is fixed in its adjusted position by means of a nut 21 on the end of the

stud-shaft 19. 22 designates studs on which are mounted to revolve bending rolls 23 which are retained in position by means of nuts 24. The studs 22 as illustrated are in 5 alinement so that an upper and a lower bending roll is provided, it being of course understood that any desired number of such bending rolls may be employed. The rolls are rounded as at 25 to suit the fillet of the 10 angle bar which is to be bent. 26 designates a die which is shown as being of annular formation and provided with a base flange 27, a step 28 and a slot 29. The die is secured to the rotary table 2 by means of 15 fastening devices 30 of any desired type.

31 designates the angle bar. Each bending roll is provided with an annular extension or shoulder 32 which engages the base flange of the angle bar.

20 In the operation, the die 26 is first secured on the rotary table 2. The carriage 12 is laterally positioned by proper actuation of the feed screw 9. The angle bar is heated and one end of it is inserted in the slot 29.

25 The position of the lower roll 23 has prior to this been adjusted to bring it into a position to contact with the angle bar by actuating the shaft 17 in the proper direction to cause the pinion 14 to move the rack 13 and 30 the slide 12 downwardly. The table 2 is revolved to cause the angle bar to be bent into a formation corresponding to the contour of the die employed. The vertical flange and fillet of the angle bar is engaged 35 by the periphery and rounded shoulder 25, respectively, of the bending roll, and the base flange is engaged by the annular shoulder 32.

When, in the operation of bending, one roll 40 becomes overheated from contact with the heated angle bars the nut 21 is loosened and the tool carrying head rotated to bring the other bending roll into operative position. The nut 21 is then tightened and the bending 45 operation repeated as described. The step of the die is such that the base flange of the angle bar will have proper support on it, thereby preventing the buckling of the outstanding leg of the die to which the angle bar conforms.

50 It will be apparent from the foregoing that in my present invention I employ a plurality of bending rolls two of which are shown in the accompanying drawings in order that an alternate use of the rolls may be employed so that when one roll becomes

overheated due to contact with the heated angle bar the other roll may be brought into operative position to engage the angle bars and effect in conjunction with the die the 60 bending of the angle bar in conformity to the contour of the die.

By the employment of such construction it is not necessary at any time to wait for a roll to cool off since as soon as a roll becomes 65 overheated another one is brought into its proper operative position.

Having thus described my invention, what I claim as new and desire to secure by Letters Patent, is:

1. In a bending machine, a rotary table, a bending die thereon, a slide supported above said die, means for adjusting said slide vertically and horizontally, a shaft projecting laterally from said slide, a tool head rotatably mounted on said shaft, bending rolls rotatably mounted on the ends of said head, and means on said tool head shaft for effecting the locking of said tool head and the 75 rollers thereon in the desired position.

2. In a bending machine, a base, a rotary table supported thereon, a die on said table, a carriage above said table, means to laterally adjust the position of said carriage, a slide on said carriage, means to vertically adjust the position of said slide, a rotatable tool carrying head, a bending roll rotatably mounted on each end of said head, a shaft projecting laterally from said slide on which said head is rotatably mounted 85 and adjustable means for securing said head in fixed position on said shaft.

3. In an angle bending machine, a rotary table, an annular stepped die thereon having an opening in its wall, adapted to receive the vertical flange of an angle bar supported on said die, a roller carrying head rotatably mounted above said table, means for imparting vertical and lateral adjustments to said head, bending rolls rotatably secured to each end of said head, said rolls having one edge rounded to engage the fillet of said angle bar, and being also provided with an outer annular shoulder to engage the base flange of said angle bar, and means 100 for locking said head and rolls in the desired position.

SAMUEL D. RONALD.
